ELECTROMAGNETICALLY ACTUATED MINIATURE VACUUM RELAY

James William Roy, Saratoga, Calif., assignor to Jennings
Radio Manufacturing Corporation, San Jose, Calif., a
corporation of Delaware

Filed Nov. 22, 1966, Ser. No. 4,816

Term of patent 14 years

(Cl. D26—13)

F/5

F/3

F/1

F/2

F/4

FIG. 1 is a front elevation of the electromagnetically actuated miniature vacuum relay, showing my new design;

FIG. 2 is a right side elevation thereof;

FIG. 3 is a left side elevation thereof;

FIG. 4 is a bottom plan view thereof; and

FIG. 5 is a top plan view thereof.

I claim:

The ornamental design for an electromagnetically actuated miniature vacuum relay, as shown.
